MODULAR DISPLAY UNIT

Paul L. Flum, 7449 Kingsbury Ave.,
University City, Mo. 63130

Filed Aug. 8, 1968, Ser. No. 13,069

Term of patent 14 years

Int. Cl. D20—02

U.S. Cl. D80—9

FIG. 1

FIG. 3

FIG. 2

I claim:
The ornamental design of a modular display unit, substantially as shown and described.
